UNITED STATES PATENT OFFICE

CROMWELL A. B. HALVORSON, OF LYNN, MASSACHUSETTS, ASSIGNOR TO GENERAL ELECTRIC COMPANY, A CORPORATION OF NEW YORK

DESIGN FOR A LAMP GLOBE

Application filed November 17, 1928. Serial No. 28,927. Term of patent 14 years.

To all whom it may concern:

Be it known that I, CROMWELL A. B. HALVORSON, a citizen of the United States, residing at Lynn, in the county of Essex, State of Massachusetts, have invented a new, original, and ornamental Design for Lamp Globes, of which the following is a specification.

In the accompanying drawing, Fig. 1 shows my ornamental lamp globe in perspective from above. Fig. 2 shows the globe in front

elevation. Fig. 3 shows the globe in side elevation. Fig. 4 is a bottom view of the globe. It will be understood that the globe is preferably formed of light transmitting or of translucent material.

I claim:

The ornamental design for a lamp globe as shown.

In witness whereof, I have hereunto set my hand this 15th day of November, 1928.

CROMWELL A. B. HALVORSON.
